US00D954090S

(12) **United States Design Patent** (10) **Patent No.:** **US D954,090 S**
(45) **Date of Patent:** **** Jun. 7, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Marcos Alonso Ruiz**, San Francisco, CA (US); **Freddy Anzures**, San Francisco, CA (US); **Greg Apodaca**, Mountain View, CA (US); **Sebastian Johannes Bauer**, San Francisco, CA (US); **Jonathan Dascola**, San Francisco, CA (US); **Alan C. Dye**, San Francisco, CA (US); **Christopher Foss**, San Francisco, CA (US); **Jonathan P. Ive**, San Francisco, CA (US); **Tiffany Jon**, Sunnyvale, CA (US); **Chanaka Karunamuni**, San Jose, CA (US); **Kenneth Kocienda**, San Jose, CA (US); **Stephen O. Lemay**, Palo Alto, CA (US); **Wan Si Wan**, Sunnyvale, CA (US); **Giancarlo Yerkes**, Menlo Park, CA (US)

(73) Assignee: **Apple Inc.**, Cupertino, CA (US)

(**) Term: **15 Years**

(21) Appl. No.: **29/718,324**

(22) Filed: **Dec. 23, 2019**

Related U.S. Application Data

(63) Continuation of application No. 29/641,013, filed on Mar. 19, 2018, now Pat. No. Des. 870,743, which is (Continued)

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet

Related U.S. Application Data

a continuation of application No. 29/538,824, filed on Sep. 8, 2015, now Pat. No. Des. 813,243.
